UNITED STATES PATENT OFFICE.

FRED H. CHAPMAN, OF WINCHESTER, MASSACHUSETTS.

ANTIREFILLING STOPPER FOR BOTTLES.

1,181,842.

Specification of Letters Patent.

Patented May 2, 1916.

Application filed December 8, 1914. Serial No. 876,057.

To all whom it may concern:

Be it known that I, FRED H. CHAPMAN, a citizen of the United States, and resident of Winchester, in the county of Middlesex and State of Massachusetts, have invented 5 certain new and useful Improvements in Antirefilling Stoppers for Bottles, of which the following is a specification.

The present invention relates to a device 10 adapted to be inserted in the neck of a bottle and constructed so as to permit the liquid contents of the bottle to be poured out, and to prevent a second filling of the bottle.

The invention particularly consists in a 15 device which, for the purposes of this description, I may call a stopper, adapted to be assembled in unit form and to be inserted in the neck of any bottle approximating a certain size, which stopper contains a valve 20 constructed and operating according to the principles of the valve shown in my prior Patent No. 1,092,559 granted April 7, 1914.

A further object of the invention is to 25 produce a stopper of the character indicated which can be made in quantities with absolute uniformity and without any such individual variations as occur in articles made of materials such as glass, porcelain, etc., and which at the same time will fit the neck of 30 any bottle of approximately the size for which the stopper is designed.

In the drawings, Figure 1 is a sectional view representing the neck of a bottle in upright position with my improved novel 35 anti-refilling stopper in place therein. Fig. 2 is a view of Fig. 1 inverted. Fig. 3 is an elevation of the inclosing shell or casing of my improved anti-refilling stopper. Fig. 4 is a plan view of the same. Fig. 5 is a plan 40 view of an abutment member which co-acts with the valve to close the same. Fig. 6 is a plan view of a baffle which co-acts with the abutment member to prevent insertion of any instrument capable of holding the valve 45 from its seat.

The anti-refilling device or stopper in 50 which my present invention is embodied consists of a number of parts assembled into a self-contained unit having substantially the form externally of a cylindrical plug adapted to fit sufficiently closely the neck of a bottle and provided with a packing to make a liquid tight contact with the walls of such neck. In construction the device includes 55 a shell 10 of generally cylindrical form and having portions of different diameters,

This shell is preferably of thin metal. In the part having the larger diameter, which is made of a size to fit approximately the interior of a bottle neck there is formed a 60 groove 11, the material of the shell being displaced inwardly so that the groove appears on the outside of the shell, while the displaced metal provides an internal shoulder 12. One end of the shell is given an inwardly tapering conical formation as shown at 13, so as to form on the inside of such portion a valve seat adapted to co-operate with a spherically formed valve. A suitable seat may, however, be made by inwardly displacing the walls of the shell on all sides at 65 some other point than the extreme end. Within the shell is contained a valve 14 having a spherical outer surface which co-acts with the inner surface of the valve seat 13. 70 This valve is preferably hollow to reduce its weight, being made as a polar zone or segment of a hollow sphere. The diameter of the rim of the segment is greater than the opening within the valve seat. Connected 75 with the valve is a stem 15 having an enlarged head 16 of which the outer end is formed as a blunt cone 17. The cone 17 and spherical valve 14 are coaxial, and the enlarged end 16 is solid and therefore relatively 80 very heavy as compared with the light and hollow shell-like valve 14. A convenient and preferred mode of construction of this valve is the following: The valve proper may be made by forming a piece of sheet 85 metal, such as aluminum, or other non-corrosive and sufficiently firm metal, into the desired form between dies under powerful pressure, and the conical end of the stem may be formed of a similar material in a 90 similar way. The valve proper and cone are then placed in a mold and molten metal is poured into the mold so as to form the stem 15, the mold being of course shaped to give the proper form to the stem and to 95 enable the plastic metal of the stem to become interlocked with the formed metal of the valve and the cone. I may use an alloy of tin and lead for the plastic metal in making the stem. Suitable proportions for the 100 alloy are one-quarter tin and three-quarters lead, but these proportions may be varied. So also may the metals of which the stem and the valve proper are made be varied.

It is to be understood that the foregoing 110 description of materials and method of manufacture employed in connection with the

- valve is not exclusive and is not intended as a limitation of the form, material, or method of manufacture of the valve. The size and shape of the valve 14 enables the same to 5 make liquid tight contact with the valve seat in any one of various positions, as well when the valve stem is inclined to the axis of the valve seat as when it is in or parallel to such axis.
- 10 The inwardly offset shoulder 12 of the casing forms a stop or rest for a combined abutment and baffle member 18. Said member is a disk having a rim 19, which bears against the shoulder 12 and has its central 15 part 20 offset from the plane of the rim. The inner periphery of the rim 19, which is also the junction between the rim and the cylindrical web or wall joining such offset part with the rim, forms an annular reaction 20 shoulder 21 adapted to co-act with the cone 17. In making the shell the shoulder 12 is put at such a distance from the reduced end, that is, from the valve seat, that the reaction shoulder 21, when placed in the shell, 25 will be at exactly the proper distance from the valve seat in order to co-act with the valve in the manner hereinafter described. Upon the offset center 20 of the abutment member is laid a baffle 23, which is a segment of a flat disk having notches 24 cut in opposite sides and having a hole 25 at one side of its center. This hole receives a struck up hump 26 on the offset part 20 of the abutment member and causes the baffle 30 to keep its desired relation to the rim 19 of the abutment member, this relation being such that the uninutilated part of the baffle overlies notches 27 in the rim 19 of the abutment member. At each side or end of 35 the notches 27, the rim 19 carries up-turned lugs 28, while on the baffle at the opposite ends of each notch 24 are down-turned lugs 29. These lugs, which cross the space between the shell and the offset part of the 40 abutment member, guard the notches in the baffles 23 and 19, and make it practically impossible for a wire or tool of any sort to be passed through the notches and between the valve and the seat, since the notches are out 45 of axial alinement, as before stated. After the baffle 23 has been put in place the edge of the casing is spun or bent over the edge of the baffle, forming a locking lip 30, shown in Figs. 1 and 2, which holds the baffle firmly 50 against the abutment member, and holds the latter against the shoulder 12.
- As previously mentioned a part of the shell has a diameter considerably smaller than the interior diameter of the bottle neck. 55 This part is shown at 31. The reduction in size of the shell provides an annular space adapted to receive a packing of cord or other material suitable for the purpose. The packing ring is shown at 32 in Figs. 1 and 2.

The anti-refilling stopper is locked in place by an expansion locking ring 33, which may be of any ordinary or other construction, and is employed in the usual way to lie partly in the groove 11 of the casing and partly in a groove formed in the interior of the bottle neck. The groove 11 is deep enough so that the ring may be contracted before the device is placed in the bottle far enough to enter the bottle neck, allowing the stopper to be pushed into the bottle until the ring arrives at the groove in the neck, when it expands and enters such groove.

The valve stem is made of such a length that the tip of the cone 17 always projects into the open central part of the abutment member, and the surface of the cone may bear at some point against the reaction shoulder 21. The conical surface acts as a wedge or cam to force the valve against its seat when the bottle lies on its side, and indeed until it is so far inverted as to be almost up side down. The preponderance of weight in the butt end of the valve stem acting through the cam surface on the end of the stem against the reaction shoulder causes the valve to be thus wedged against the seat after the bottle has been tilted beyond the horizontal position, that is when the mouth of the bottle is below the body of the same. 95 When the bottle has been tilted beyond the critical angle, the entire valve will drop as shown in Fig. 2 until the cone enters the central opening or cavity of the abutment member as far as the width of the opening permits and the valve then becomes separated from its seat. The critical angle referred to is that between the axis of the bottle and the horizontal when the bottle has been so far tilted or over-turned that the conical face on 100 the end of the valve stem begins to slide across the abutment shoulder toward the mouth of the bottle, and is not reached until the bottle has been tilted beyond the point at which the under side of this conical surface 105 becomes horizontal.

Among the advantages which flow from the principles hereinbefore set forth are the following: The stopper may be made in large quantities by automatic machinery at 115 comparatively small cost, and all the stoppers of the same size are duplicates of one another and adapted to fit any bottle neck of one standard size. The stopper is independent of the variations in size and shape from the standard of individual bottle necks, by reason of the packing ring or band 32, which adapts itself to all such irregularities, and thus any of the stoppers of a certain size is adapted to make a liquid tight fit in any bottle of approximately the corresponding size. The valve and seat being made of metal by dies can be made liquid tight in each stopper without special operations, such as are required where a valve seat is cast or blown in 120 125 130

5 a bottle. The abutment member and valve seat being in the same casing are at an invariable distance apart, which is the proper distance for the best operation of the valve, and there is no possibility of this distance being changed, as there is in constructions 10 where the seat for the valve and the abutment for the valve-closing device are independent or separable. The stopper being made as a unit may be shipped from the maker to the customer in assembled condition ready to be slipped into a bottle. The stoppers shipped in any lot may be taken out as they come and placed in bottles without becoming disassembled or disarranged, and particularly without requiring skilled labor to put them in. The use of the stopper requires no modification in the construction of the bottle itself with the sole exception of the shallow groove on the inside of the neck which receives the locking ring. Such a groove can be readily formed in the bottle in the process of making it, and can almost as 20 readily be formed in bottles already made.

25 What I claim and desire to secure by Letters Patent is:

30 1. An anti-refilling stopper comprising a metal shell having an internal valve seat and having a lateral internal shoulder, an abutment member set against said shoulder, means holding said abutment member rigidly in place, said member having a reaction shoulder, and a spherically formed valve co-acting with said valve seat and having a stem with a conical outer end co-acting with 35 said reaction shoulder.

40 2. An anti-refilling device comprising a shell made in one piece with one end drawn toward its axis to form an internal valve seat and having between its ends an inwardly offset annular portion forming a shoulder within the shell and a groove on the outside of the shell, a combined abutment and baffle member placed in the shell 45 abutting against said shoulder, a co-operating baffle member set on said abutment member, the edge of the shell being headed over and interlocked with the edge of said co-operating member, and a valve co-acting with 50 said valve seat and having a stem formed with a conical wedge portion engaged with said abutment member.

55 3. In a non-refillable bottle, in combination with a valve and a valve seat, a baffle member consisting of a disk having a notch in its rim and having its central part offset from the plane of such rim, means for supporting said member, a co-operating baffle 60 consisting of a disk lying upon the offset part of the first disk and having a notch in its rim, and means for preventing removal of the co-operating baffle, the disks being so placed that the notch of one is overlaid by 65 the nonmutilated part of the other.

4. In a non-refillable bottle, in combination with a valve and a valve seat, a baffle member consisting of a disk having a notch in its rim and having its central part offset from the plane of such rim, and a co-operating baffle consisting of a disk lying upon the offset part of the first disk and having a notch in its rim, the disks being so placed that the notch of one is overlaid by the nonmutilated part of the other, and each disk 70 having lugs at each end of its notch extending toward the other disk.

5. An anti-refilling bottle stopper including a shell having an internal shoulder, a combined abutment member and baffle made 80 as a disk set in the shell with its rim resting on said shoulder and its central part offset so as to provide a central recess and a reaction shoulder bounding said recess, the rim of said member having an opening to permit outflow of liquid, a co-operating baffle disk lying across the offset part of said member within the end of the shell and having a peripheral opening out of direct alignment 85 with the opening of said member, an inwardly directed flange on the shell overlying the rim of said baffle disk retaining the same in place, a valve seat in the shell at the side of the abutment member opposite to the side on which the co-operating baffle is located, 90 and a spherical valve co-operating with said seat, said valve having a stem projecting into the recess of the abutment member and formed with a conical wedge surface on its end arranged to bear on the said reaction 95 shoulder.

6. A bottle stopper adapted to permit outflow of the contents of the bottle and prevent a second filling of the same, comprising a tubular metal shell made in one 105 piece from end to end having its inner end contracted to form a valve seat and having an internal bead between its ends, such bead forming a shoulder on the inside of the shell and a groove on the outside 110 adapted to receive a lock or ring, a combined baffle and abutment member located in said shell and bearing at its periphery on said bead, said member having an annular shoulder within its periphery, means for 115 securing said member in the shell and a valve arranged to fit said valve seat and having a stem extending toward said member, the stem being formed with an end face projecting across the plane of said 120 annular shoulder and adapted to bear against the annular shoulder.

7. A stopper for preventing filling of a bottle, comprising a generally cylindrical shell having a portion near one end of reduced diameter to provide a space adapted to receive packing and being further reduced in diameter at the extreme end to provide a valve seat, the part of said shell having greatest diameter being formed 125 130

- with an internal bead which provides a shoulder on the interior and a groove on the exterior of the shell.
8. In an anti-refilling stopper, a shell having an internal shoulder, a combined baffle and abutment member comprising a disk fitting in the shell and its periphery bearing against said shoulder and having a notch in its rim and upturned lugs at the opposite edges of said notch, the disk having an axially offset central portion which forms a cavity and an annular shoulder surrounding said cavity, and a complementary baffle disk bearing on said offset portion and having in its periphery a notch and lugs at each end of said notch projecting toward the first-named baffle, the notch of one baffle being out of axial alinement with the notch of the other baffle, and the shell having an inwardly turned lip overlying the rim of the second baffle and locking the two baffles in place.
9. In an anti-refilling stopper, a shell having an internal shoulder, a combined baffle and abutment member, comprising a disk fitting in the shell and its periphery bearing against said shoulder and having a notch in its rim and upturned lugs at the opposite edges of said notch, the disk having an axially offset central portion which forms a cavity and an annular shoulder surrounding said cavity, and a complementary baffle disk bearing on said offset portion and having in its periphery a notch and lugs at each end of said notch projecting toward the first-named baffle, the notch of one baffle being out of axial alinement with the notch of the other baffle and said baffles having complementary abutments for placing and holding one relatively to the other with their notches in such relation, and the shell having an inwardly turned lip overlying the rim of the second baffle and locking the two baffles in place.
10. An anti-refilling bottle stopper comprising a shell having an internal valve seat and adapted to fit within the neck of a bottle, a valve in said shell coöperating with said seat, and baffle means for preventing insertion of an instrument capable of holding said valve away from the seat, said baffle means comprising two disks fitting within said shell between the end thereof and the valve, the inner disk being centrally offset in a manner such as to form an annular wall, and the outer disk being placed upon said offset portion, each disk having a notch in its peripheral part and being so arranged that an un-notched part of its rim overlies the notch of the other disk, and the shell having means for retaining said disks in place.
11. An anti-refilling bottle stopper comprising a shell having an internal valve seat and adapted to fit within the neck of a
- bottle, a valve in said shell coöperating with said seat, and baffle means for preventing insertion of an instrument capable of holding said valve away from the seat, said baffle means comprising two disks fitting within said shell between the end thereof and the valve, the inner disk being centrally offset in a manner such as to form an annular wall, and the outer disk being placed upon said offset portion, each disk having a notch in its peripheral part and being so arranged that an un-notched part of its rim overlies the notch of the other disk, and each disk having lugs flanking its notch and extending toward the other disk, said lugs coöperating with said annular wall to prevent passage of an instrument by the disks into proximity with the valve.
12. An anti-refilling bottle stopper comprising a shell having a valve seat and being adapted to fit the neck of a bottle, a valve in said shell coöperating with said seat, and baffle means obstructing the shell between the valve and that portion of the shell which lies nearest the mouth of the bottle, said baffle means comprising two sheet metal disks set within the shell and one of them having its center axially offset and having in its rim a notch, and with integral up-turned wings or lugs at each end of said notch, and the second disk being placed against the offset center of the first disk and having a notch in its periphery flanked by integral up-turned wings which project toward the rim of the first disk, the said disks being so placed that their notches are out of alinement.
13. In combination with a bottle closing valve having a wedge stem, a combined baffle and abutment for said wedge stem comprising a disk having its center offset to provide a cavity at the side of the disk toward the valve stem and a reaction shoulder surrounding said cavity, the said offset center at the other side of the disk serving as a spacing element, and a second baffle disk bearing against such spacing element, the disks having passages respectively out of alinement and located between their respective peripheries and the said offset center of the first-named disk.
14. A bottle stopper adapted to prevent refilling of a bottle, comprising a cylindrical shell adapted to fit the neck of a bottle and having a section of reduced diameter, an annular packing surrounding said reduced section, the balance of the shell being adapted to fit closely within a bottle neck and having an encircling groove, a spring locking ring contained in said groove adapted to expand into locking engagement with the bottle neck, a portion of the shell being reduced to form a tapered valve seat, a spherically formed valve complementary to said valve seat having a stem with a weight-

ed wedge-like end, and an abutment mounted in said shell in position to coöperate with said wedge-like end, said wedge-like end and said abutment being relatively disposed where they will be brought into engagement whenever the stopper is tipped from upright position.

Copies of this patent may be obtained for five cents each, by addressing the "Commissioner of Patents, Washington, D. C."

In testimony whereof I have affixed my signature, in presence of two witnesses.
